UNITED STATES PATENT OFFICE.

WILLIAM SCHWARTZ, OF ELIZABETH, NEW JERSEY.

PAINTING-MACHINE.

SPECIFICATION forming part of Letters Patent No. 367,242, dated July 26, 1887.

Application filed March 21, 1887. Serial No. 231,666. (No model.)

To all whom it may concern:

Be it known that I, WILLIAM SCHWARTZ, a citizen of the United States, and a resident of Elizabeth, Union county, New Jersey, have 5 invented certain Improvements in Machines for Use in Painting Shingles and the like, of which the following is a specification.

My invention relates to that class of machines employed in mechanically coating shingles, laths, &c., with paint. My machine is not designed to apply the paint mechanically to the shingle, but after the shingle has been dipped in a paint bath and inserted in the machine the latter removes the surplus paint from 15 the faces and edges of the shingle and smooths the coat.

The object of my invention is to produce a simple and effective machine that will operate equally well on shingles of different widths and 20 thicknesses, and one that will be durable and easily cleaned.

My invention will be hereinafter fully described, and its novel features carefully defined in the claims.

25 In the drawings, which serve to illustrate my invention, Figure 1 is a vertical longitudinal mid-section of my improved machine. Fig. 2 is a front end view, and Fig. 3 is a plan, of my improved machine.

30 Before proceeding to describe my invention in detail, I will say that in using the machine the shingles are first dipped in a paint bath and entirely covered with the paint. The workman then takes the shingle from the bath 35 and passes it, thin end first, between face-wipers, which form a part of the machine, pushing it through the wipers far enough for its end to enter between a pair of revolving rubber-faced rollers. These serve to smooth and 40 lay the coat of paint on the faces of the shingles and to feed the latter on into the machine. The shingle now encounters two self-adjusting edge-wipers, which wipe the paint from the edges. It is then nipped and forwarded by a 45 second pair of revolving rubber-faced rollers, which further smooth its faces, and finally deliver it at the back of the machine. Suitable scrapers and receptacles for the surplus paint are provided, as will be described.

50 A represents a stout frame, preferably of cast-iron. This frame is designed to support the operative parts of the machine.

B B represent the first pair of rubber-faced smoothing and feeding rollers, and B^x B^x represent the second or last pair of rollers. These 55 pairs of rollers are or may be precisely alike.

I will say here that I do not confine myself to any particular proportions; but I usually make these rollers about four inches in diameter and sixteen inches long. They will usually 50 have iron cores and be faced with vulcanized rubber, similar to the ordinary "wringer" rollers. In order that the rollers may all be driven positively in unison, I provide the rollers of each pair with intermeshing toothed 65 gear-wheels C C, and arrange between the gear-wheels, on the upper rollers of the pairs, a toothed driving-wheel, C^x, on a cross-shaft, D, the teeth of said wheel C^x meshing at its opposite sides with those of the two upper 70 gear-wheels, C. On the other end of shaft D is a crank, D^x, whereby said shaft may be rotated by hand. A belt-pulley may, however, be substituted for the crank, so that the rollers can be driven by power. The upper 75 rollers of each pair are held down by spring-pressure, their journals finding bearings in boxes a a, mounted in slots or slideways b in the machine-frame. Extending across the machine, and its ends resting on said boxes a, is 80 a spring-bar, E. There are two of these bars, one for each upper roller of each pair.

F is a leaf-spring, the ends of which rest in the bars E in recesses formed in the same. In order to keep the spring F in place its ends 85 are provided with slots b^x, and screws c are driven through these slots into the bars E.

At the middle of the machine-frame is a cross-bar or bridge, G, and through a central boss on this bridge is driven a screw, H, the 90 end of which bears on the crown of spring F. By means of the screw the tension of the spring may be regulated.

I I^x are the two wipers, between which the dipped shingle is primarily inserted. These 95 are of vulcanized rubber, by preference, and about as long as the rollers. The lower wiper, I, is fixed, being attached to a cross-bar, J, secured to the machine-frame. The upper beveled edge of this lower wiper stands normally about on the same level as the top of the lower roller. The bar J^x, to which the upper wiper is secured, is mounted to play up 100 and down in guide-slots d in the machine-

frame. I usually make said bar of iron and rely upon gravity to keep it pressed down; but it might be pressed down by a spring or springs.

5 In Figs. 1 and 3 I have represented a shingle, X, as having been placed in the machine and as being carried forward by the rollers B B. It will be seen that the wipers I I^x are slightly bent over at their edges by the moving shingle. These wipers might, however, be made so thick as not to so flex or bend. Just in advance of the lower wiper, I, I have shown a small roller, K. This is merely designed as a guide for the insertion of the shingle and to keep the rear end of the shingle from dropping after it has passed entirely through the wipers.

After the advancing end of the shingle X has fairly entered the space between the pairs 20 of rollers it encounters the edge-wipers L L. These are alike, and a minute description of one will suffice for both. These wipers project out from opposite sides of the machine, preferably obliquely, as shown. They need 25 not meet, as it is only necessary they should encounter the narrowest as well as the widest shingle, and the narrowest shingle will not be less than three inches wide. The edge-wiper comprises an arm, e, fixed to a hinge-axis, e^x, 30 rotatively mounted in a vertical bearing in the machine-frame. On the free end of arm e is a wiper-plate, e', of vulcanized rubber or some suitable yielding material, that will remove the surplus paint from the edge of the 35 shingle. On the hinge-axis e^x is a coil-spring, e^z, one end of which is secured to the machine-frame and the other to said axis. This spring holds the arm e up to a suitable stop, e^z, normally, but the advancing shingle is free to 40 swing it around on its hinge-axis and force a passage between said wipers.

M is a bed extending across the machine, its upper surface being a little below the level of the upper surface of the lower rollers. The 45 wiper-arms e rest on and play over this surface; but in order that the rubber wiper-plate e' may project a little below the lower surface of the shingle, and thus assure the thorough wiping of the edge of the latter, I form a recess, g, in the bed M, for the free ends of the edge-wipers L to play in. This recess also serves to receive and collect the paint removed, which flows down to the lower part of said recess and out through a hole or holes, f, whence 55 it drips into a suitable receiver, N, below.

The shingles will vary in width from about four to fifteen inches ordinarily. The operator in feeding the machine will take care that the axis of the shingle, whatever may be its 60 width, will coincide approximately with the axis of the machine. Then the edge-wipers L will yield equally for the passage of the shingle. However, it is not essential to the operation of the machine that great care be exercised in this respect. If the shingle be not entered as above described the first pair of feed-

rollers will carry it through straight, or nearly so.

After the shingle has advanced far enough its leading end will be seized by the last pair 70 of rolls, B^x B^x, and it will be carried through and delivered at the back of the machine. The shingles eventually slide down a chute or inclined way, m, of any kind.

As the rollers will collect more or less paint 75 on their surfaces, I provide them with scrapers and troughs for carrying off the surplus paint. The scrapers for the upper or self-adjusting rollers are alike, and those for the lower fixed rollers are alike. The troughs are 80 substantially alike in all four. I will describe one of each.

In front of the upper roller, B^x, is hung a scraper-bar, h, preferably of wood. This scraper is secured to one lip of a sheet-metal 85 trough, h^x, the other lip of said trough being attached to swinging arms h^{xx}, one at each end of the trough, suspended from the machine-frame at w. A spring or springs, h', connecting said arms to studs h^z on the frame, 90 hold the scraper h up elastically to the upper roller, B^x, and allow said roller to play up and down. The sheet-metal trough slopes from one end to the other, and the paint collected therein flows to the lower end and drips thence 95 down into the recess g in bed M.

The scraper for upper roller, B, is constructed in the same way, and the same letters of reference are employed to designate its parts. However, in the case of this scraper, the inclined or sloping trough discharges down by a pipe, h^z, directly into the receiver N.

The scraper for the lower roller, B^x, comprises the scraper-bar i, of wood, the sloping sheet-metal trough i^x, and hinging-lugs i^z, 105 hinged to brackets i^z on the machine-frame. As these lower rollers do not play up and down, an elastic pressure is not necessary, and screws i^z, screwing through the brackets and bearing on the trough or the lugs i^z, serve to set the 110 scraper-bar up against the roller. These scrapers for the lower rollers discharge the paint collected directly into the receiver N. From the receiver N the paint may flow out at an outlet, j, and into a paint bath arranged below. 115 I have not deemed it necessary to show this bath or receptacle for the paint. It may be of any kind and be arranged in any convenient way. For example, the machine may be screwed to a bed, Y, of wood, in the nature of a platform, and this platform be secured on the top of a large paint holder or tank near its side, so that the shingles can be taken from said tank by the left hand of the workman while his right hand grasps crank D^x. 120

Weights might be substituted for the springs F and e^z with good results; but I prefer the construction shown. I consider weights as the mechanical equivalents of springs in this construction.

I am well aware that in machines for this and analogous purposes it is customary to em- 130

ploy feeding rolls to feed the strip or thing to be painted and revolving brushes to spread and smooth the paint; and I am also aware that it is common in these machines to employ 5 scrapers or "doctors" to remove the surplus paint from said revolving parts. I do not apply the paint with my machine; nor do I employ any revolving brushes or rollers to spread the paint. My object in arranging the rubber 10 wipers $I I^x$ in advance of the first pair of feeding-rollers is this: The shingle when taken from the paint bath is dripping with paint. If it were passed in this condition directly between the feed-rollers, these latter would soon 15 become so coated and fouled with paint as to render the machine useless; but the wipers $I I^x$ remove this surplus paint, and only a very little reaches the feed-rollers. My object is not especially to spread the paint, but to wipe off 20 the surplus. The rubber-faced feed-rollers serve to smooth the coat. I do not think the removal of the surplus paint can be accomplished, practically, by means of revolving brushes.

25 Having thus described my invention, I claim—

1. In a machine for use in painting shingles and the like, the combination, with a pair of feed-rollers, B B, of the fixed bar J, the rubber 30 face-wiper I, secured thereto, the bar J^x , mounted in guides, so that it may play up and

down, and the rubber face-wiper I^x , secured thereto, the said rollers and wipers being arranged with respect to each other substantially as shown and described.

2. In a machine for use in painting shingles and the like, the combination, with a pair of feed-rollers, B B, of the edge-wipers L L, each comprising an arm, e, a hinge-axis, e^x , having a bearing in the frame of the machine, the 40 wiper-plate e' , and the spring e^2 , all arranged substantially as set forth.

3. The combination, with the feed-rollers, of the bed M, having a recess, g, and the hinged edge-wipers L L, having wiper-plates e' 45 depending into said recess g in the bed, substantially as and for the purpose set forth.

4. The combination, with the feed-rollers, of the recessed bed M, the yielding edge-wipers L L, having their free ends depending into said 50 recess, whereby the surplus paint is allowed to fall into said recess in the bed, and the receiving pan N, said recess in the bed having an outlet, f, over the pan, substantially as set forth.

In witness whereof I have hereunto signed 55 my name in the presence of two subscribing witnesses.

WILLIAM SCHWARTZ.
